UNITED STATES PATENT OFFICE.

HARRY T. ANDERSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

DOOR-OPERATING MECHANISM.

1,160,559.

Specification of Letters Patent.

Patented Nov. 16, 1915.

Application filed November 25, 1914. Serial No. 874,013.

To all whom it may concern:

Be it known that I, HARRY T. ANDERSON, a citizen of the United States, and resident of Butler, in the county of Butler and State of Pennsylvania, have invented a new and useful Improvement in Door-Operating Mechanism; and I do hereby declare the following to be a full, clear, and exact description thereof.

10 My invention relates to door operating mechanism.

The invention has relation more particularly to the type of door operating mechanism which is illustrated and described in 15 Letters Patent of the United States, No. 1,064,879, granted to me June 17, 1913, in which a movable latch is carried by the door at the outer end, with a winding-chain connected to the latch whereby the latch 20 is drawn forward and supported by the winding-shaft when the door is closed, so as to relieve the weight on the chain and support the door directly on the shaft.

In the present invention, the latch has a 25 rack-face which is engaged by a pinion on the winding-shaft which is of a common construction now in use so that the last movement of the latch is accomplished by the engagement of the pinion with the rack-face, and whereby a positive movement is 30 imparted to the latch in unwinding to start the operation of opening the door.

In the patent referred to, the latch-member moves in a casing having platforms at 35 different levels with a roller interposed between said latch member and the upper platform of said casing, and a roller interposed between the upper face of said latch-member and the lower face of the door. 40 It is found, however, in practice that these rollers are liable to skew when the door is opened or closed, and the said rollers consequently become jammed in the casing so as to prevent the proper operation of the 45 device.

One of the objects of my invention is to so mount these rollers as to prevent this skewing, and also to provide for the adjustment of the toothed pinion on the shaft to 50 bring it into proper alinement with the latch-bar.

In the drawing, Figure 1 is a plan view of a portion of a bottom of a railway car showing my invention applied thereto; Fig. 55 2 is an enlarged section on the line 2—2,

Fig. 1; Fig. 3 is a section on the line 3—3, Fig. 1; Fig. 4 is an enlarged plan view of a portion of the winding shaft and portion of the car door; Fig. 5 is an enlarged view of a portion of the section shown in Fig. 3; 60 Fig. 6 is an end view of the latch and its casing; and Fig. 7 is a section on the line 7—7, Fig. 5.

In the drawing, the numeral 2 designates the bottom of a suitable car provided with 65 openings closed by the doors 3. These doors may be arranged in pairs on each side of the center-sill of a car, said door being hinged by suitable hinges 5 to the car-body. Each door is provided with one or more 70 movable latch-members 6 adapted to move back and forth in the casing 7. The latch-member is supported at its rear end within the casing 7 upon the roller 8, which rests upon the bottom-plate 7a. The bolt 9 forms 75 a stop for the roller and controls the outward movement of the latch-member 6. The outer end of the latch-member is bifurcated to form the two arms 10 and 11, which project out beyond the door. The chain 80 13 is connected to the ring 14 of the arm 11, and said chain is adapted to wrap around the winding-shaft 15.

The arm 10 has the rack-face 16, which is adapted to engage the toothed-pinion 17 on 85 the winding-shaft 15. The winding-shaft is provided with the opening 18, and the pinion 17 has the collar 19 with staggered openings 20 formed therein adapted to register with the opening 18 in the winding-shaft, and the bolt 21 in passing through 90 said openings secures the collar 19 in position. By having the staggered openings as above, the position of the pinion 17 may be readily adjusted so that the pinion is 95 brought into proper alinement with the rack-face 16 of the arm 10 so that said rack-face will fully engage said pinion, and so bring the wear on all parts of said pinion 100 equally.

A roller 23 is interposed between the upper face of the latch-member and the door to provide for the easy movement of the latch-member in moving in and out.

The rollers 8 and 23 are provided with 105 the annular grooves 24, and said grooves are engaged by the ribs 25 on the latch-member. This engagement of the ribs 25 with the rollers prevent said rollers from skewing and becoming jammed in the cas- 110

ing in advancing or withdrawing the latch-member. It must be remembered that in the case of railway-cars carrying ore, coal or other like material, these doors are subjected to severe usage, and when the winding-shaft is turned to lower the door, just as soon as the rack-face of the latch-member disengages the pinion 17, the weight of the contents of the car causes the door to swing back with great violence, and unless the rollers are guided properly, this sudden swing is liable to skew said rollers and cause them to jam so that the door is prevented from opening properly. By my invention by the employment of the ribs 25 engaging the annular grooves in the rollers, all this difficulty is obviated and the roller moves true in its guides. Furthermore, if for any reason in the construction of the car, it is found that the latch-member is so arranged that the rack-face does not properly engage the pinion, the pinion may be readily adjusted by moving the bolt and moving the same so as to bring the staggered 25 openings into register and the pinion is securely fixed in position.

What I claim is:

1. In a door-operating mechanism, the combination with a car-body, of a downwardly swinging door, a casing secured to the lower side of said door, a movable latch-member in said casing, a roller movable to

and fro in said casing and engaged by said latch-member, and means for holding said roller against skewing. 35

2. In door-operating mechanism, the combination with a car-body, of a downwardly swinging door, a casing secured to the lower side of said door, a movable latch-member in said casing, a roller engaging said casing and engaged by said latch-member, said roller having an annular groove formed therein, and a rib on said latch-member engaging said groove. 40

3. In door-operating mechanism, the combination with a car-body, of a downwardly swinging door, a casing secured to the lower side of said door, a movable latch-member in said casing having a rack-face at the outer end, a winding-shaft, a chain connected to said latch-member engaging said winding-shaft, a pinion on said winding-shaft, a collar on said pinion having staggered openings, said shaft having an opening adapted to register with said openings in said collar, and a fastening device engaging said openings. 45 50

In testimony whereof, I the said HARRY T. ANDERSON have hereunto set my hand.

HARRY T. ANDERSON.
